CLAIM

The ornamental design for a lift table, as shown and described.

DESCRIPTION

FIG. 1 is a front and top perspective view of a lift table showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is an enlarged view of an encircled portion of the lift table labeled 8 shown in FIG. 1.

FIG. 9 is an enlarged view of an encircled portion of the lift table labeled 9 shown in FIG. 1.

FIG. 10 is an enlarged view of an encircled portion of the lift table labeled 10 shown in FIG. 5; and,

FIG. 11 is an enlarged view of an encircled portion of the lift table labeled 11 shown in FIG. 7.

The broken lines encircling claimed subject matter depict the cut line of the enlarged views and form no part of the claim. All other broken lines depict portions of the article and form no part of the claimed design.
